US0D1020366S

(12) United States Design Patent (10) Patent No.: US D1,020,366 S
(45) Date of Patent: * Apr. 2, 2024

(54) VEGETABLE CUTTER

(71) Applicant: Wendong Liu, Jiujiang (CN)

(72) Inventor: Wendong Liu, Jiujiang (CN)

(73) Assignee: Wendong Liu, Jiujiang (CN)

() Term: 15 Years

(21) Appl. No.: 29/877,133

(22) Filed: Jun. 2, 2023

(30) Foreign Application Priority Data

May 29, 2023 (EM) 015023052-0001

(51) LOC (14) Cl. 07-04

(52) U.S. Cl.

(57) CLAIM

The ornamental design for a vegetable cutter, as shown and described.

DESCRIPTION

FIG. 1 is an exploded front perspective view of a vegetable cutter, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a closed state view; and,

FIG. 10 is a usage state view thereof.

1 Claim, 10 Drawing Sheets
